UNITED STATES PATENT OFFICE.

JOHN KELLY, OF NORFOLK, VIRGINIA.

BUTTON-ATTACHING MACHINE.

1,128,456.

Specification of Letters Patent. Patented Feb. 16, 1915.

Application filed May 21, 1913, Serial No. 768,965. Renewed October 3, 1914. Serial No. 364,945.

To all whom it may concern:

Be it known that I, JOHN KELLY, a citizen of the United States, residing at Norfolk, in the county of Norfolk and State of Virginia, have invented certain new and useful improvements in Button-Attaching Machines; and I do hereby declare the following to be a full, clear, and exact description of the invention, such as will enable others skilled in the art to which it appertains to make and use the same.

My invention relates primarily to button attaching machines, has especial reference to providing means whereby buttons of different colors can be carried by the machine to be applied to shoes of different colors without displacing buttons of one color to furnish buttons of another color.

The invention has for its object economy in time and labor and consists in certain improvements in construction, which will be fully disclosed in the following specification and claims.

In the accompanying drawings Figure 1 is a side elevation of a button attaching machine of conventional form provided with my improvements. Fig. 2 is a plan view of the double hopper with the covers removed, and also showing parts of the button chutes. Fig. 3 is a vertical transverse section of the hopper on line 3—3, Fig. 2. Fig. 4 is a top plan view of the hopper with the covers in closed position and showing parts of the button chutes. Fig. 5 is a plan view of one of the covers detached. Fig. 6 is an enlarged detail vertical section on line 6—6, Fig. 4. Fig. 7 is a like vertical transverse section on line 7—7, Fig. 4. Fig. 8 is a longitudinal vertical section taken through the inner wall of one half of the hopper member showing parts in elevation and the projecting parts of the adjacent hopper portion being omitted. Fig. 9 is an enlarged vertical transverse section on line 9—9, Fig. 1.

Reference being had to the drawings and the designating characters thereon, the numeral 1 indicates a button attaching machine of conventional form, comprising the rod 2, attached to a treadle or other source of power, not shown, at one end, and to one arm 3 of a crank for imparting motion to the machine. 4 is a shaft, on which a com-

pound crank 5 is mounted. One arm 6, of this crank is connected to a bar 7 by its 55 wrist pin 8 engaging a slot 9 in the bar and held in position by a latch 9', and imparts intermittent rotary motion to the button feed-wheel 10 through the crank 11, ratchet-wheel 12 mounted on shaft 13, driving pawl 14 and locking pawl 15 on pivoted lever 16. The inner ends of the shaft 13 engage the partition 18 and are supported therein. These several parts described and all the other parts of the machine head not thus far 65 described, are of well known construction, form no part of my invention, and therefore require no further elucidation.

17 indicates the hopper or button receptacle, provided with a vertical longitudinal 70 partition 18 separating the hopper into two separate button receptacles, chambers or compartments 19, 20, each of which is provided with a button feed wheel 10 of known form, having V-shaped radial arms 21 for 75 agitating and raising the buttons into the raceways 22, 22' respectively in each hopper, each hopper being a duplicate of the other, and at opposite ends of the hoppers are secured button-chutes 23, 23' which register with the race-ways 22, 22' as shown in Figs. 1, 2, 4 and 8 and conduct the buttons to the attaching mechanism located at 24, of well known construction. The chutes are secured to the hopper by screw-bolts 25 engaging suitable holes, and the chutes form convenient handles for turning the hopper into and out of operative position.

26 indicates an arm extending from the body of the machine, in the end of which is 90 a socket 27 engaged by a spherical member 28 on a stud 29 extending from the hopper supporting frame 29', and the two members 27 and 28 form a ball and socket or universal joint by means of which the hopper 95 can be swung laterally into and out of operative position and elevated or tilted back if required in the manipulation of the hopper. By tilting or turning the hopper the feed chutes may be positioned beyond the 100 head of the machine.

The section of the hopper in use to supply buttons is secured in operative position by a spring 30 on the arm 30' engaging a pin 31 extending or projecting laterally 105 from one side of the button-chutes 23, as

shown in Figs. 1 and 9. This locking of the chutes in use in position also locks the entire hopper against accidental displacement.

32 in Figs. 2, 3 and 8 indicates levers pivoted on posts 33, extending to the race-ways 22, 22' at their upper ends, and each projected into a race-way by a spring 34 secured against turning on post 35 and engaging pin 37 and post 33 both of which are mounted on the lever 32 for dislodging any buttons that may stick in the race-way. The levers are returned by cams 38 on shafts 13 engaging a projection 39 on lever 32, as shown in Fig. 8, and the levers are located in recesses 38' in the partition 18.

Each half of the hopper is provided with a cover 41 pivotally secured to the body of the hopper by a rod 42 engaging lugs 43 and 44, and each cover is provided with an extension or flange 45 to cover the race-ways 22, 22' adjacent to the chutes 23, 23' for removing buttons that may become disarranged in and choke the chute. The partition 18 is provided with an extension 46, shown in Figs. 3 and 7 on which the covers 41 rest at their adjacent edges and are supported thereon, and each chamber 19, 20 is provided with an opening in its bottom supplied with a door 47 for removing buttons from the hopper.

Each hopper chamber 19, 20 is designed to be supplied with buttons of a selected color, and as either of the chambers is brought into operative position, the bar 7, must be disengaged from the crank 11 on the hopper last used and attached to the corresponding crank on the hopper to be put in use, and the connection between the bar and the crank is secured by a spring 11' secured to the outer face of the crank, as shown in Figs. 1, 2 and 3.

Surplus buttons raised by the wheel 10 are directed into a recess 48 by an inclined 45 guard 49 and are returned into the hopper.

From the foregoing it will be observed that a single actuating mechanism for the twin hoppers may be employed and that by slipping the bar 7 from its attaching position with the extension of the ratchet 11 in turning the hopper one-half around and coupling the companion ratchet extension with the end of the bar the hopper is usable with different buttons from that of the companion hopper. This change can be readily effected and the machine rendered useful for different types of buttons.

While the special button setting machine is outlined in the drawings, it is to be understood that the improvements are adapted for use with other types of machines.

It is to be further understood that changes in the construction and arrangement of the parts can be made without departing from

the general nature and spirit of the invention.

Having thus fully described my invention, what I claim is:

1. A device of the class described comprising a laterally movable and reversible hopper arranged to coöperate with the button setting mechanism, and having adjacent button receptacles and a race-way in each receptacle and a button chute attached to 70 and alined with each race-way, and provided with a universal joint or bearing, so that when the hopper is revolved one receptacle is swung out of operative position and the other receptacle is brought into 75 operative position, and a button-feed device in each receptacle.

2. A device of the class described comprising a laterally movable and reversible hopper arranged to coöperate with the button setting mechanism, and having adjacent button receptacles and a race-way in each 80 receptacle and a button chute attached to and alined with each race-way and provided with a universal joint or bearing, 90 so that when the hopper is revolved one receptacle is swung out of operative position and the other receptacle is brought into operative position, a button-feed device in each receptacle, and a cover for each receptacle having a flange extending over its race-way to prevent buttons rising therein, each button chute being in operative alinement with a race-way and forming a handle for revolving said hopper. 100

3. A device of the class described comprising a laterally movable and reversible hopper arranged to coöperate with a button setting mechanism, a partition in said hopper forming two separate compartments 105 for different kinds of buttons, and a race-way in each compartment, and provided with a universal joint or bearing, so that when the hopper is revolved one receptacle is swung out of operative position, and the other receptacle is brought into operative 110 position, button raising devices for each compartment, means for dislodging buttons in each race-way, and button-chutes connected to the hopper and in alinement with 115 the race-way of each compartment.

4. In a device of the class described in combination with a button setting machine head, a button supplying means comprising a movable hopper arranged to coöperate 120 with the button setting mechanism and having adjacent button receptacles and race-ways, button chutes for association with the hopper, means for adjustably mounting the hopper to permit a turning and tilting 125 movement thereof, so that when the hopper is moved in one direction one receptacle is located out of operative position and the other receptacle is brought into operative position, a button feeding device in the 130

respective receptacles, and means operable upon the operation of the machine for operating said button feeding means.

5. A device of the class described comprising a movable hopper arranged to co-operate with the button setting machine and having adjacent button receptacles and raceways, a button chute, a bracket on the machine, adjustable connections between the bracket and the hopper, button feeding means in the receptacles, and a single means operably associated with the machine for actuating the feeding means, said means comprising a detachable coupling fashioned 15 to engage either of the button feeding means.

6. A device of the class described comprising a rotatable and tilttable and reversible hopper arranged to co-operate with a button setting mechanism and having adjacent button receptacles, a raceway for each receptacle, and a jointed bearing for the hopper comprising means for securing the hopper in position and permitting its movement 25 so that when the hopper is moved in one direction one receptacle is swung out of operative position and the other receptacle is brought into operative position.

7. A device of the class described comprising a laterally movable and reversible hopper arranged to co-operate with the button setting mechanism and having adjacent button receptacles and a raceway in each receptacle, a button chute aligned with each raceway and the hopper provided with a universal joint or bearing so that when the hopper is revolved one receptacle is swung out of operative position and the other receptacle is brought into operative position,

40 a button feed device in each receptacle, and a cover having a flange extending over a raceway to prevent buttons rising therein.

8. In a button setting machine, a button hopper pivotally and tiltably supported on

the machine, providing two button chambers 45 each having a discharge, one opposite the other, a button chute, and means for locking the chute to the hopper.

9. In a button setting machine, a button chute, a hopper, means for pivotally and 50 tiltably supporting the hopper on the machine, and a plurality of button receptacles in the hopper, having independent discharge openings arranged to co-operate with the button chute for feeding buttons to the machine.

10. In a button setting machine the combination with a hopper having a plurality of button compartments and a discharge raceway in each compartment of means for 55 adjusting the various compartments from an operative position to an inoperative position comprising a pivotal and swinging connection.

11. In a button setting machine the combination with a button supply hopper comprising two like chambers separated one from the other, of button feeding devices in said chambers, button discharging chutes for the chambers, and means for adjusting the 60 hopper to align the discharge chute with the machine setting mechanism comprising a pivotal and tilttable connection, substantially as described.

12. In a button setting machine the combination with feeding mechanism, comprising a hopper having a plurality of button receiving chambers with feeding mechanism in the chambers, of means for pivotally and 65 tiltably supporting the hopper on the machine.

In testimony whereof I affix my signature, in presence of two witnesses.

JOHN KELLY.
